UNITED STATES PATENT OFFICE.

CHARLES T. MASON, OF SUMTER, SOUTH CAROLINA, ASSIGNOR TO THE SUMTER TELEPHONE MANUFACTURING COMPANY, OF SUMTER, SOUTH CAROLINA, A CORPORATION OF SOUTH CAROLINA.

TELEPHONE-SWITCHBOARD.

SPECIFICATION forming part of Letters Patent No. 787,930, dated April 25, 1905

Application filed February 4, 1905. Serial No. 244,203.

To all whom it may concern:

Be it known that I, CHARLES T. MASON, a citizen of the United States, residing at Sumter, county of Sumter, State of South Carolina, 5 have invented certain new and useful Improvements in Telephone-Switchboards; and I do hereby declare the following to be a full, clear, and exact description of the invention, such as will enable others skilled in the art to which it 10 appertains to make and use the same.

The invention relates to drop and jack mechanisms for telephone-switchboards, and has for its object to provide a unitary drop structure capable of being applied to and removed 15 from the jack-strips without dissociating any of the parts of the drop, said drop having spring-contacts adapted to engage coöperating contacts on the jack to automatically establish circuit connections between the drop 20 and jack, said drop and jack also having co-operating contacts to automatically connect the current of a night-bell or other subsidiary signal when the drop is applied to the board.

The invention has for a further object to 25 provide a pivoted shutter coöperating with the magnet-armature to lock the latter in attracted position to hold the night-bell circuit closed, said shutter being locked by the armature in its retracted position, and means comprising a pendular lever coöperating with the 30 shutter to restore the latter, said pendular lever having a finger projecting beyond the face of the drop to be engaged by the jack-plug or by the finger of the operator to re- 35 store the shutter.

These and other details of the invention are more particularly pointed out in the appended specification and claims and are illustrated in the accompanying drawings, in which—

40 Figure 1 is a plan view of the improved drop and a fragment of the coöperating jack-contacts. Fig. 1^a is a rear end view of the drop. Fig. 2 is a longitudinal section of the drop, showing the shutter in normal or re- 45 tracted position. Fig. 3 is a corresponding view of the forward portion of the drop and the coöperating jack, the shutter being in exposed position. Fig. 4 is a front elevation of

the drop with the shutter exposed. Fig. 5 is a section corresponding to Fig. 3, showing 50 the operation of the plug in restoring the drop. Fig. 6 is a front elevation of the drop with the shutter withdrawn. Fig. 7 is a sectional plan view of a jack looking from below. Fig. 8 is a longitudinal section through 55 three jack-strips, showing two drops in side elevation applied thereto. Fig. 9 is a plan view of one end of a jack-strip. Fig. 10 is a diagram of a jack and drop and the circuits 60 coöperating therewith.

In the drawings, A indicates a drop, which consists of a generally rectangular frame b, in which is supported a horizontally-disposed electromagnet a, which is removably secured in said frame by a screw c passing through 65 the rear of said frame into the core of the magnet, as illustrated in Fig. 2. Secured to the magnet a and projecting rearwardly therefrom are two springs a', which constitute the circuit- 70 terminals of the magnet-coil, and in order to permit the ready insertion and removal of the magnet with respect to the inclosing casing b the end of the latter is recessed, as at b', to receive the projecting springs a', as indicated in Figs. 1^a and 2. Pivoted on the cross-pin 75 c, mounted in the sides of the casing b, is a rectangular armature d, the vertical member of which coöperates with the core of the magnet a, and the horizontal member moves in a vertical plane as the armature swings for a 80 purpose hereinafter more particularly described. Pivoted on a transverse pin g, mounted in the lower part of the casing b and in front of the lower end of the armature d, is a shutter f, the forward end of which is adapt- 85 ed to fall by gravity through a slot j in the front face of the drop A when said shutter f is released. Projecting rearwardly from the pivotal point of the shutter f is a tail having two detents f", f''' extending from the upper 90 and lower sides thereof and so disposed with respect to the end of the armature d that when the shutter f is retracted it is locked in this position by the armature d, which engages the end of the tail behind the detent f''' and 95 when said armature d is attracted the detent

f' on the tail of the shutter engages the lower end of said armature and locks the armature in attracted position until the shutter is restored, as indicated in Figs. 2 and 3, respectively.

- It is to be noted that the shutter *f* is mounted entirely within the drop-frame and that the only portion extending beyond the same is the end of said shutter when said end is projected through the slot *j* in the face of the drop *A*. In order to restore the drop, therefore, there is provided a pendular lever *k*, consisting of a U-shaped frame pivoted at its upper end upon a transverse pin *l*, mounted in the sides of the casing so that said lever lies snugly between the sides of the casing *b*, in the rear of the front face thereof and in juxtaposition to the shutter *f*. The bottom of said U-shaped frame is provided with a forwardly-extending angular finger *k'*, which projects through the lower side of the casing, and a rearwardly and upwardly extending finger *k''* which passes through a slotted portion of the shutter *f* and engages a tongue *h*, projecting from said shutter and formed of the metal struck out of the slot through which the finger *k''* passes. It is to be noted that when the shutter *f* is in exposed position the tongue *h* engages the finger *k''*, so that when the pendular lever *k* is swung to the rear by pushing upon the forwardly-extending finger *k'* the shutter *f* is given a corresponding rocking movement until the tail thereof catches the end of the armature *d*, as shown in Fig. 5.
- As above explained, the shutter is adapted to be restored manually by the operator, who pushes the finger *k'* inwardly, and thereby swings the pendular lever *k* to restore the shutter; but it is also the purpose of this invention to permit the shutter to be restored by the insertion of the operator's plug in the jack *B* corresponding to the particular drop, and to attain this object the drop *A* is so mounted with respect to the jack *B* that the finger *k'* on the pendular lever *k* lies just above and in front of the plug-socket, so that the shoulder on the plug *p* when said plug is inserted in the jack *B* forces the finger *k'* backward, and thereby rocks the pendular lever *k* to restore the shutter *f*.
- The jacks *B* are preferably arranged in strips, each strip containing a number of jacks disposed in horizontal relation, each jack consisting of the usual plug-socket, the plug-actuated jack-springs *t w*, which project rearwardly from the strip and are adapted to be connected with the line-circuit, and the two intermediate strips *u v*, which are engaged by the respective springs *t w* when the plug is withdrawn and serve to establish the circuit through the coil of the drop-magnet. The rear projecting ends of the strips *u v* are provided with upwardly-extending contact members *u' v'*, which lie in the path of the contact-springs *a'* of the drop-magnet, so that

when the drop is placed in position on the jack the ends of the springs *a'* are guided into contact with the jack-strips *u v* between the flaring ends *u' v'* thereof, as indicated in Figs. 1 and 7.

The drops are applied to the jack-strips in the manner indicated in Fig. 8—that is to say, the several drops are slid into position between the jack-strips so that the contact-springs *a'* of the drop engage the corresponding strips *u v* of the jack next below it and the projecting finger *k'* of the shutter-restoring lever lies just above and in front of the jack-plug socket. It is to be noted that the drops may be applied to or removed from the jack-drops without dissociating any of the parts of the drop and that the mere insertion of the drop automatically establishes the circuit between the jack-strips and the drop-magnet, and, furthermore, that the drop may be entirely removed from the switchboard without interrupting the line-circuit. Where a night-bell or other auxiliary signal is used, it is desirable that the circuit therefor be also automatically established when the drop is applied to position, and to this end there is mounted upon the under face of the jack-strip, next below the particular drop two stationary contacts *r' s'*, which are connected to the night-bell circuit. Coöoperating with these contacts *r' s'* are two contact-springs *r* and *s*, connected to the rear face of the drop and having upwardly-extending spring portions projecting forwardly and over the body of the drop. The spring-contacts *r* and *s* are connected to spring-strips *m* and *n*, respectively, which latter are supported at one end between the same insulating-blocks which connect the springs *r* and *s* to the rear face of the drop, as indicated in Figs. 1 and 2. The spring *m* is secured at its forward end to a stud *m'*, located upon a cross-pin in the casing *b* and provided with a set-nut *m''*, by means of which the forward end of the spring *m* may be raised or lowered. The forward end of the spring *n* is free and is provided with a contact which is adapted to be brought into engagement with the spring *m*, thereby completing the night-bell circuit. This latter operation is effected by the horizontal member of the armature *d*, which engages the forward end of the spring *n* and forces the same into engagement with the spring *m*, so that the night-bell circuit is closed as long as the armature *d* is held in attracted position, either by reason of the current flowing through the magnet *a* or the locking effect of the shutter *f* when the latter is in exposed position.

Having thus described my invention, what I claim, and desire to secure by Letters Patent, is—

1. The combination in a drop, of a magnet, a pivotal armature coöperating therewith, a pivotal shutter coöperating with the armature

to lock said shutter in retracted position, and to lock the armature in attracted position, and means projecting beyond the face of the drop for restoring the shutter after the same has 5 been actuated.

2. The combination in a drop, of a magnet, a pivotal armature coöperating therewith, a pivotal shutter coöperating with the armature to lock said shutter in retracted position, a tail on the shutter to lock said armature in attracted position, and means projecting beyond the face of the drop for restoring the shutter after the same has been actuated.

3. The combination in a drop, of a magnet, 5 a pivotal armature coöperating therewith, a pivotal shutter having a tail coöperating with the armature to lock the latter in attracted position, and to lock said shutter in retracted position, and a pendular lever having a finger 10 o projecting beyond the face of the drop, whereby the shutter is retracted.

4. The combination in a drop, of a magnet, a pivotal armature coöperating therewith, a pivotal shutter having a tail coöperating with 5 the armature to lock the latter in attracted position, and to lock said shutter in retracted position, and a pendular lever having a finger projecting beyond the face of the drop and a second finger engaging the drop, whereby 15 o said shutter may be restored by operating said lever from the front of the drop.

5. The combination in a drop, of a magnet, a pivotal armature coöperating therewith, a pivotal shutter having a rearwardly-extend- 5 ing tail coöperating with said armature to lock the latter in attracted position and to lock said shutter in retracted position, means projecting beyond the face of the drop whereby the shutter is restored, and a signal-circuit 20 o and terminals therefor closed by the armature while the latter is in attracted position.

6. The combination of a drop, comprising a magnet, a pivotal armature coöperating therewith, a pivotal shutter having a tail coöperating with said armature to lock the latter in attracted position and to lock said shutter in retracted position, a pendular lever for restoring the shutter having a finger projecting beyond the face of the drop, and a jack below the drop, 25 o said finger overhanging the jack to be engaged by a plug inserted in the jack.

7. The combination of a drop having a slot

in its face through which the shutter falls, and a pendular lever pivoted behind the face of said drop and adapted to engage the shutter, 55 said lever having a finger projecting beyond the drop-face by which the lever is swung to restore the shutter.

8. The combination of a drop having a slot in its face through which the shutter falls, a 60 pendular lever pivoted behind the face of said drop and adapted to engage the shutter, said lever having a finger projecting beyond the drop-face, and a jack below said drop to receive the plug which engages the finger to swing the 65 pendular lever and restore the shutter.

9. The combination of a drop having a magnet provided with spring-contacts secured thereto, a jack on which said drop is mounted and provided with spring-contacts, and means 70 o on the jack-contacts to guide the magnet-contacts into engagement with said jack-contacts when the drop is placed in position on the jack.

10. The combination of a drop having a mag- 75 net provided with spring-contacts secured thereto, a jack on which said drop is mounted and provided with plug-engaging spring-con- 80 tacts and intermediate contacts, the latter hav- ing flared wings or extensions to guide the magnet-contacts into engagement with said in- termediate jack-contacts when the drop is placed in position on the jack.

11. The combination of a drop-frame, a mag- 85 net removably mounted therein, and contact- springs secured to said magnet and removable therewith, said frame having a cut-away por- 85 tion to receive said contact-springs.

12. The combination of a series of drops, jack-strips between which said drops are re- 90 movably supported, coöperating contacts on the drops and jacks to automatically establish 95 the drop-circuits when the drops are applied to the jack-strips, auxiliary signals operated by the drops, contact-springs on the drops, and fixed contacts on the jack-strips, whereby the auxiliary signal-circuits are also established when the drops are applied to the jack-strips.

In testimony whereof I affix my signature in presence of two witnesses.

CHARLES T. MASON.
